US0D1023693S

(12) **United States Design Patent** (10) **Patent No.:** **US D1,023,693 S**
(45) **Date of Patent:** **** Apr. 23, 2024**

(54) **JUICER ATTACHMENT**

(71) Applicant: **Guangzhou Aishell Trading Co., Ltd.**,
Guangzhou (CN)

(72) Inventor: **Mengke Ling**, Guangzhou (CN)

(**) Term: **15 Years**

(21) Appl. No.: **29/818,753**

(22) Filed: **Dec. 10, 2021**

(51) **LOC (14) Cl.** **31-00**

(52) **U.S. Cl.**

USPC **D7/665**

(57) **CLAIM**

The ornamental design for a juicer attachment, substantially as shown and described.

DESCRIPTION

FIG. 1 is a top, front and left side perspective view of a juicer attachment, showing my new design;

FIG. 2 is a bottom, rear and left side perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The broken lines in the drawings illustrate the portions of the juicer attachment, which form no part of the claimed design.

1 Claim, 8 Drawing Sheets
